UNITED STATES PATENT OFFICE.

WILLIAM ERASTUS WILLIAMS, OF WILMETTE, ILLINOIS.

STEEL ROOF FOR RAILWAY BOX CARS.

Application filed March 22, 1926. Serial No. 26,529.

My roof relates to that class of freight box car roof wherein I-beam carlines are used and roof covering sheets which are sufficiently stiff due to their peculiar construction that no underlying sheeting is required under the roof sheet itself.

The object of my invention is to provide a roof including the carline construction which will have a minimum weight and a maximum strength and at the same time will stand weaves and twists of the car body itself without tearing the roof sheets. The further object of my invention is to provide a roof construction which may be built into the car with the least possible expense. A particularly valuable feature in this roof construction is the forms and shapes of the end of the carlines and roof sheets to make secure closure at the ends of the roof sheets over the ends of the carlines.

Reference will be had to the accompanying drawings in which

Fig. 1 is a plan of a roof sheet being one of the sections of roof sheet which extend from eave to eave of the car.

Fig. 2 is an edge elevation of the roof sheets shown in Fig. 1.

Fig. 3 is a transverse section from eave to eave of the car through the central portion of one of the roof sheets which would correspond to section 3—3 of Fig. 1 as relates to the roof sheet itself.

Fig. 4 is a plan view showing a roofing joint over one carline.

Fig. 5 is a plan on an enlarged scale of a portion of the roof at the eaves showing the termination of the carline.

Fig. 6 is an enlarged section on line 6—6 of Fig. 5.

Fig. 7 is a view corresponding to the left of Fig. 3 but on a larger scale than that shown in Fig. 3.

Fig. 8 is a longitudinal vertical section between two carlines along the region of the ridgepole.

Fig. 9 is a perspective view showing the shape of the end of one of the carlines.

Fig. 10 is a transverse elevation across the running board looking from the left end of Fig. 8.

Fig. 11 is a plan of a modified form of a roof sheet the modification relating to the ends of the channel edges of the roof sheets.

Fig. 12 is an elevation of a portion at

the eave of the car showing the modified sheet as per Fig. 11.

The frame construction at the top of the car is composed of any suitable sideplates but the cross section of the sideplate here shown is indicated in Fig. 7 and is a special Z-bar construction having an outer vertical eave leg 2 and inclined horizontal flange 3 and vertical flange 4 and inclined roof fastening flange 5. However, any suitable sideplate may be used with my roof.

The cross or roof frame members of the car is composed of carlines of I-beam section having a top flange member 6, a web 7 and a lower flange 8. These I-beams are bent in the form of an arch as indicated by Fig. 3 to form the roof shedding incline as desired.

At the ends of the carlines flanges and web are cut away as shown in Fig. 9, the top flange being sheared on an incline 9 and tapering down to a parallel portion 10, and cut away entirely at the outer end whereat the vertical web 7 is sheared off in the curved line 11, leaving a portion of the lower flange 8 extending outward free of the web 7 and this portion is turned down into vertically arranged flange 12.

The carline thus shaped at the ends is secured to the flange 5 of the sideplate by means of the rivets 13 passing through the holes 14 in the lower flange 8 of the I-beam. This lower flange 8 of the I-beam is further secured to the vertical leg 4 of the sideplate through the medium of knee brace pieces having a web 15 secured by rivets 16 and by riveted-over portion 17 to the lower flange 8 of the I-beam and this knee brace piece is provided with bracing flanges 18 and with the web portion 19 secured by rivets 20 to the vertical leg 4 of the Z-bar sideplate.

Thus, the I-beam carline is securely fastened to the sideplate. The purpose of shearing the ends of the I-beam carline, as shown by Fig. 9, is to provide for a closure of the roof sheets over these portions of the I-beam without requiring any clips or cover plates of any kind to cover over the ends of the roof sheets and the ends of the carlines.

The roof sheets thus furnish the entire covering for the top of the car without any clips or cover pieces or brackets of any kind. Each sheet, excepting the end sheets at each

end of the car, are exactly alike and they extend from carline to carline and over the tops of the carlines, one edge of the roof sheet fitting snugly over the edge of the carline while the other edge of the same sheet fits over the carlines and the edge of the other sheet, as best understood from Fig. 8 wherein 21 shows the right edge of the central sheet shown in Fig. 8 and 22 shows the left end of the sheet.

Thus, one edge of the roof sheet fits down on the carline itself while the other edge fits over the top of the roof sheet already on the carline. I call the shape of these edges of the roof sheet channels. Hence, one edge of the roof sheet is stamped up having a slightly wider channel than the other edge. The wide channel portion of the roof sheet is indicated by 24 and the narrow edge by 25 in Fig. 1. Immediately adjacent to this channelled edge of the roof sheet the body of the sheet curves down into the flat portions 26 and the middle portion of the sheet is pressed upward into a large corrugation or bulge 27. The channel portions 24 and 25 are narrowed down at their ends as indicated by 28 and 29 in Fig. 1 to cover over the narrow portions of the ends of the I-beam carlines as shown in Fig. 9.

In the modified form of roof sheet as shown in Figs. 11 and 12 the ends 23 of the channel edges 24 and 25 of the roof sheet are not narrowed as in the other figures but extend full width down over the ends of the carlines thus leaving a clearance across the narrow portions 10 and 11 of the carlines. In other respects the roof sheets are alike.

The ends of the roof sheet are bent downward into downward projecting flanges 30, the middle portions of which are curved under as indicated by 31, see Fig. 7, turning under an edge of the flange 5 of the side-plate, while at each edge or corner of the roof sheet the downward projecting flange 30 extends straight downward and where these flanges overlap, as is indicated by Fig. 5 and where they cover over the downward projecting portion 12 of the lower flange of the I-beam carlines 8 they are riveted to each other and to this flange 12 by rivets 32 which rivets 32 pass through the holes 33 in the flange 12 of the carline. The ends of the roof sheets are also held down onto the sideplates by the turned under portions 31 which extend under the flange 5 of the side-plate. This turning under of this portion 31 is done after the roof sheets are assembled in place on top of the carlines.

Any suitable ridgepole construction may be used as desired and a wooden ridgepole 34, as here shown, is secured by bolts 35 to the lower flange 8 of the I-beam carline.

Any suitable running board saddle may be used with this construction and I have shown a saddle composed of a flat plate 36 to which

are riveted by rivets 38 brackets 37 having lower legs 39 secured by bolts 40 passing through the flanges of the I-beam carline.

A packing piece of asphalt felt roofing 41 is interposed between the legs 39 and the roof sheet on top of the carlines to insure against leakage of water in and around the head of the bolt 40 and further insurance against leakage is provided by a lead washer 42 under the heads of the bolts 40. A running board 43 is secured by bolts 44 to the plate 36.

Where purlins are desired to be used they may be secured in a similar manner to that of the ridgepole 34 and any suitable form of ridgepole or purlins may be used.

The bulge or corrugated portion 27 in conjunction with the valleys 26 on each side of the bulge 27 together with the channelled edges 24 and 25 of the roof sheets furnish a very stiff sheet across the car which does not require any underlying sheathing when using a relatively light weight metal.

The shape of the sheets across permit, as it were, a spring or twist of the roof sheet 90 which will accommodate for any twist or winding of the car body that may occur in service.

In assembling the roof sheets on to the carlines the sheets are simply dropped down consecutively along the length of the car, one edge of the sheet overlapping the edge of the other sheet and so on which permits the cheapest assembling possible in a construction of this kind.

The fastening down of the running board saddle hold the sheets down in the middle of the car and the rivets 32 at each end of the roof sheet hold the ends of the roof sheet down and the rivets 32 are assisted in this by the turned under portions 31 of the lower flanges 30 of the roof sheets.

At each end of the car a special sheet is provided having a turned down flange that may be needed to fit over the end of the car depending, of course, on the character of the end that is used in the car structure.

Carlines cut away at the ends, as described, form, as it were, rounded downwardly curved noses at the eaves and I have shown the channelled edges of the roof sheets curved to fit curved ends due to the cutaway of the top flange of the I-beam carline as shown.

I have disclosed novel features in this application which are also disclosed in my co-pending applications Ser. Nos. 86,817 and 88,229, and I expressly reserve the right to claim any novelty disclosed, but not claimed, herein in another co-pending application.

What I claim is:

1. In a car roof construction of the class described, an I-beam carline having the top flange cut away in a tapering form at the ends with the web of the carline cut away

in a curved downward form and with the lower flange of the I-beam cut away from the web of the I-beam and bent downward in a downward projecting flange and with 5 the body of the I-beam having its web vertically arranged extending across the car.

2. In a roof of the class described, roof sheets extending from eave to eave of the car and having upturned edges turned over 10 into channelled shapes and adapted to interlock and overlap each other, the said roof sheets being provided with upwardly extending centrally arranged bulges thus creating valleys between the flanged channelled 15 edges of the sheet and the central bulges the said channelled edges being curved downwardly at the corners of the sheets and terminating in vertically arranged flanges, said flanges extending across the ends of the 20 sheets and secured at their middle portions to the sideplates and at the corners of the sheets to the carlines.

3. In a roof structure of the class described, I-beam carlines with their webs vertically arranged, roof sheets having channelled edges overlapping each other and the carlines, a running board saddle secured to the top of the roof sheets by means of bolts which extend down through the channelled 25 edges of the roof sheets and secured against leakage by washers of soft material interposed between the parts that are clamped together.

4. In a roof structure of the class described, roof sheets having channelled edges overlapping each other and overlapping the tops of the carlines and the said sheets extending across from eave to eave of the car in arched form and having a cross section 30 in the form of a relatively deep valley on each side of the carline and a relatively deep summit in the middle portion of the sheet and the said summit tapering down to a flat surface where the roof sheets rest on 35 the sideplates.

5. In a structure of the class described,

carlines extending normally in a zone higher than the sideplates and the body of the said carlines curved downward at their ends over the sideplates, roof sheets having 40 channelled edges overlapping the tops of the carlines and having on each side of the carline a relatively deep valley corresponding to substantially the zone of the top surface of the sideplates and the said sheets 45 provided with a central upward projecting corrugation curved downwardly merging in a flat portion at the sideplates of the car and the ends of the said roof sheets turned down into downward projecting flanges over 50 the edges of the sideplates and the said channelled edges of the roof sheet likewise curved down over the curved ends of the carline and the said roof sheets secured from upward displacement at the eaves of the car 55 and at the running board saddle's position at the summit of the roof.

6. An I-beam carline having each end downwardly curved by the removal of a portion of the web and upper flange and said 60 flange being transversely tapered by the removal of portions adjacent to said ends.

7. An I-beam carline having at each end a downturned extension of the lower flange, the upper flange and the web terminating in 75 a downwardly rounded nose, and the upper flange tapered from said nose.

8. In a car roof structure, the combination with an I-beam carline having each end downwardly curved by severing a portion 80 of the web and upper flange and said flange being tapered by severing end portions, of a plurality of roof sheets each having two lateral channels, one of which fits over the top flange and tapered and curved ends of 85 said carline and the other of said channels being adapted to enclose a channel identical with said first channel.

Signed at Chicago, in the county of Cook and State of Illinois, this 19th day of March, 90 1926.

WILLIAM ERASTUS WILLIAMS.
